UNITED STATES PATENT OFFICE.

GARDNER M. SHERMAN, OF SPRINGFIELD, ASSIGNOR TO THE LAMB KNITTING MACHINE MANUFACTURING COMPANY, OF CHICOPEE FALLS, MASSACHUSETTS.

VAPORIZER.

SPECIFICATION forming part of Letters Patent No. 436,063, dated September 9, 1890.

Application filed October 4, 1889. Serial No. 325,989. (No model.)

To all whom it may concern:

Be it known that I, GARDNER M. SHERMAN, of Springfield, in the county of Hampden and State of Massachusetts, have invented a new and useful Improvement in Vaporizers, of which the following is a specification, reference being had to the accompanying drawings, forming part thereof.

My invention relates to apparatus for securing the vaporization of liquids for disinfecting or deodorizing purposes.

In Letters Patent of the United States issued to me July 29, 1887, and numbered 366,693, I have shown, described, and claimed an apparatus of this nature comprising a vessel having openings at the top and near the bottom thereof, with means for closing said openings to any desired extent, and a receptacle for the liquid, formed from porous material, located within said vessel in such manner that an annular space surrounding the receptacle is provided, whereby the liquid which percolates through the porous body of the receptacle can be caused to evaporate freely and, when the vessel is open, to escape to the surrounding atmosphere. It is of the utmost importance in this class of apparatus that as large an area of the surface of the liquid as possible be exposed to the air to facilitate evaporation thereof, and, while the porous receptacle in my said previous apparatus thus exposes a very large area of said surface, I have found that a still greater area of the surface of the liquid can be directly exposed to the action of the air, while the possible clogging of the pores of a porous receptacle with long-continued use can be avoided.

It is the object of my present invention, therefore, to provide a vaporizing apparatus in which a very extended area of the liquid will be directly exposed to the air, with means for accurately regulating the admission of air thereto and its escape therefrom, as distinguished from what may be called an "indirect exposure" of the liquid through the pores of a porous receptacle.

To this end my invention consists in the vaporizing apparatus comprising a vessel having means for admitting air thereto at or near the bottom thereof and for permitting air to escape therefrom at or near the top thereof,

and a series of receptacles for liquid located within said vessel, as hereinafter fully described, and particularly pointed out in the claims.

Referring to the drawings, in which like parts are designated by like letters in the several figures, Figure 1 is a central vertical section of a vaporizer constructed according to my invention. Fig. 2 is a plan view thereof with the top or cover removed. Fig. 3 is a partial side elevation showing the air-port at the bottom of the same. Fig. 4 is a view of the inner side of the valve for closing said air-port. Fig. 5 is a vertical central section of a modified form of the apparatus. Fig. 6 is a front elevation thereof with the closing means removed. Fig. 7 is a view in perspective of the closing means. Fig. 8 is a plan view of the apparatus with the closing means removed, as in Fig. 6.

Referring to Figs. 1 to 4, inclusive, the letter A designates a cylindrical vessel, which will preferably be made of iron or other metal to increase its durability and to lessen its liability to be upset when in use. Said vessel is made with a tight bottom, and at the top is provided with a cover having means whereby an opening of any desired extent can be formed into said vessel. I prefer to utilize substantially the same means for this purpose that are shown in my said previous patent, the same consisting of a cover A', having depending therefrom a threaded stem a, located centrally in said cover, which stem enters a threaded hole a', centrally located in a bridge-piece a², extending diametrically across a rim a³, which rim closely fits the upper end of the vessel A. The rim is thus adapted to be removed from the vessel when desired, together with the bridge-piece and cover, while by revolving the cover in one direction it will be caused to descend upon the rim and to make a tight joint therewith, and by turning it in the opposite direction it can be elevated above the rim to any desired extent, thereby accurately governing the size of the opening at the top of the vessel.

Thumb-pieces a⁴ upon the cover enable it to be readily operated, as described.

At or near the bottom of the vessel A is an air-inlet port a⁵, across which extends the

bridge-piece a^6 , having at the center thereof the threaded hole a^7 , which hole receives the stem a^8 of a cover or valve a^9 . The valve a^9 terminates upon its inner side in an annular bearing-surface, as shown in Fig. 4, whereby said valve is adapted to tightly close said air-port when screwed down upon the latter, while its threaded stem enables it to accurately govern the admission of air through said port. The vessel is also preferably provided with a bracket a^{10} , projecting from its upper end and having a hole therein, by means of which the vessel can be suspended from a nail or hook, if desired.

15 The means for holding the liquid within said vessel preferably consists of a series of open receptacles located at different heights within the latter and having an air-circulating space both around and between said receptacles.

As shown in Figs. 1 and 2, said receptacles consist of circular pans or trays having outwardly-flaring sides supported upon a tube b' , which extends centrally through the bottom of each receptacle, its upper end being substantially flush with the upper edge of the upper receptacle. The greatest diameter of the receptacles b is sufficiently less than that of vessel A to form an annular air-space surrounding the former, as shown, while the depth of said receptacles is such as to leave an open space between the bottom of each one and the level of the liquid in the one beneath it.

35 As a means of retaining the series of receptacles at the center of the vessel, I prefer to utilize stem a of cover A' of the latter and a projection a^{12} , centrally located upon the bottom of the vessel, which stem and projection enter opposite ends of tube b' ; but it will be understood that other means for securing this result can be utilized, if desired.

The vaporizer thus constructed can be readily charged for use by removing rim a^3 , with the cover A', from the top of the vessel, withdrawing from the latter the series of receptacles, pouring into the latter the desired quantity of liquid, taking care that the level of said liquid in any receptacle does not lie 45 above the level of the bottom of the receptacle above it, and then restoring said parts to their normal positions. When the vaporizer is thus charged, it can be set upon the floor or suspended from the wall of the room 55 in which it is to be used, and by opening air-port a^5 and raising cover A' a circulation of air upwardly through vessel A will be caused. The extended area of the surface of the liquid which is exposed to the air by the receptacles 60 b secures a very rapid evaporation of the liquid, said area being materially increased by the flaring sides of the receptacles. If but a slight discharge of the vapor into the surrounding atmosphere is desired, port a^5 is left 65 closed and the cover is raised but slightly.

By the use of the series of receptacles b , I not only secure a greater area of exposed sur-

face of the liquid than would be possible with a single porous receptacle of a corresponding height and diameter, but I also avoid the possibility of a loss of power to the apparatus through the clogging of the pores of such a receptacle. It will be obvious, however, that by making the receptacles b from porous material the power of the apparatus herein shown could itself be considerably increased, and I contemplate employing such construction in cases where a vaporizer of extreme power is desired.

In Figs. 5 to 8, inclusive, I have shown a modified form of the invention, in which the letter C designates a vessel which is rectangular in cross-section instead of round. I prefer to make the bottom, rear side, and the two ends of said vessel integral with each other and to make the top and front side integral with each other in the form of a closing device C'. A bar c extends from one endpiece to the other at the front side of the vessel and midway between the top and bottom thereof, said bar having at the center thereof the enlargement c' and outwardly-projecting stud c^2 , which stud is threaded at its outer end to receive a thumb-nut c^3 . The front side piece forming part of the closing device is provided with a slot c^4 , through which projects the stud c^2 , and by means of which said closing device can be adjusted vertically, it being held in any position to which it may be adjusted vertically by said nut c^3 . A finger-piece c^5 on said front side piece enables the latter to be raised and lowered readily. By raising said closing device, as shown in Fig. 5, openings are formed both at the top and bottom of the vessel C to permit air to circulate through said vessel, the size of which openings can obviously be regulated by raising said device more or less.

Upon the inner side of each of the end pieces of the vessel are located cleats c^6 for supporting the ends of a series of receptacles C^2 for the liquid, said cleats being preferably made in the form of bent bars or rods, as shown, whereby provision is made for an upward circulation of air at the ends of the receptacles C^2 . Said receptacles consist of rectangular pans or trays having flaring sides and ends and are of such width as to leave an air-space between their sides and the sides of the vessel, as shown in Fig. 5.

The operation of this form of the apparatus is the same as that previously described, and the great extent of the surface of the liquid which is exposed to the air renders the last-described form one of even greater power than that first described.

The main portion of the vessel C can be cast in a single piece by causing the bottom and the cleats c^6 to stand at a slightly-obtuse angle to the rear side to enable the vessel to be drawn from the mold, as will be obvious to persons skilled in the art.

Any of the disinfecting or deodorizing liquids usually employed can be used in con-

nnection with the apparatus herein shown and described.

The size of the vessel and the number of receptacles for liquid can be varied at will to correspond to the use for which the particular apparatus is intended.

It is obvious that the receptacles in the form first described could be supported upon cleats, as in the second form; but I prefer to utilize the tube b' , as it enables the entire series of receptacles to be removed from and replaced in the vessel A together, and also retains them in vertical alignment.

Modifications in construction other than those suggested herein can be made without departing from the spirit of my invention.

Having thus fully described my invention, what I claim, and desire to secure by Letters Patent, is—

1. The vaporizer herein described, comprising an inclosing-vessel having an air-inlet opening at or near the bottom thereof and an air-outlet opening at or near the top thereof, valves for governing said openings, and a series of receptacles for a disinfecting-liquid, supported within said vessel at different heights, said receptacles being of such dimensions that an air-passage between the sides thereof and the inner surface of the inclosing-vessel is formed, substantially as and for the purpose set forth.

2. In a vaporizer, the combination, with an inclosing-vessel having openings at or near the top and bottom thereof and valves for closing said openings, of a series of receptacles for liquid, located within said vessel, said receptacles being arranged one above the other and secured to a common support, substantially as set forth.

3. In a vaporizer, an inclosing-vessel having openings at or near the top and bottom thereof and valves for closing said openings and having upon the inner side of the bottom thereof a centrally-located projection, and a series of open receptacles for liquid, mounted upon a support extending centrally through the bottom of each, said support having its lower end constructed to receive said projection at the bottom of said vessel, substantially as and for the purpose described.

4. In a vaporizer, the combination, with vessel A, having rim a^3 detachably secured thereto, said rim carrying the bridge-piece a^2 , having the threaded hole a' at the center thereof, of cover A', having threaded stem a , and tube b' , carrying the series of open receptacles b , arranged and operating substantially as described.
